UNITED STATES PATENT OFFICE

2,373,163

APPARATUS FOR RECONDITIONING
DRILL PIPE

John F. Cailloux, Houston, Tex., and Philip M. Rea, Oklahoma City, Okla.

Application June 15, 1942, Serial No. 447,184

12 Claims. (Cl. 113—102)

The invention relates to well-drilling apparatus and, more particularly, to drilling collars, couplings, connecting members, or subs as the same are utilized in drill strings, such as are ordinarily employed in the rotary process of drilling wells. A drill stem or drill string such as ordinarily employed in rotary well-drilling is made up of a plurality of sections of drill pipe coupled directly together or coupled together through the medium of drilling collars, subs, connectors, or the like; and, due to the fact that drill string is continuously rotated as well as being frequently moved longitudinally inside of a well casing, the exterior surfaces are subjected to almost continuous wear, and consequently, are either reduced in diameter around their entire surface, or are worn flat at various points. This wear, of course, weakens the string and it therefore limits the life of the various members which constitute the string.

Considerable effort has been made in the past few years to perfect methods of building up or re-surfacing the drill string members adjacent their coupling points so as to avoid junking the entire member. Such efforts are evidenced by the following listed United States patents:

Pate, 2,232,135 (Feb. 18, 1941)
Huntsinger, 2,247,173 (June 24, 1941)
Stone, 2,262,211 (Nov. 11, 1941)
Stone, 2,259,232 (Oct. 14, 1941)
Stone, 2,262,212 (Nov. 11, 1941)
Stone, 2,262,210 (Nov. 11, 1941)

Previous to the advent of the re-surfacing methods disclosed in the above-listed patents, some attempts had been made to re-sleeve drill stem joints by turning them down and then pressing a heated tubular sleeve over the turned down portion, the sleeve shrinking into intimate contact with the stem as it cooled. In carrying out that method, the sleeve was next welded to the stem around each end. The impractical part of that process lay in the fact that the inside of the sleeve had to be turned out perfectly so that it would exactly fit the turned down portion of the drill stem section. This made the process somewhat expensive, although the method was found to reach a result which was entirely practical after it had once been accomplished.

These applicants have conceived a re-surfacing method wherein the sleeve does not have to be turned out interiorly, but which will also reach the desired result originally obtained by shrinking the sleeve into place upon the drill stem member. In accomplishing the process of the present

invention, a tubular element is longitudinally split down one side, and after being heated to expand and render the same bendable, it is rolled on to the previously turned down portion of the drill stem member, and is held in place therearound mechanically while being weld-integrated to the drill stem member. The weld is made along the longitudinal line of cleavage, as well as around both ends of the sleeve. This method makes it possible to use scrap pipe for forming the sleeve, as well as permitting use of flat steel plate, when desired, to originally form the split sleeve.

In carrying out the present invention, a mechanical device is used to roll the sleeves upon the drill stem sections and to hold them in place under desired pressure until the welds can be made. This machine, as well as the method of applying the sleeves, is the subject matter of the present patent application.

One of the prime objects of the present invention is to provide a new re-sleeving method for drill stem members which will be economical and practical.

Another object is the provision of a machine capable of carrying the re-sleeving method into effect.

A further object is the provision, in such a machine, of structure capable of compensating for and handling various sizes of work.

A still further object is the provision, in such a machine, of structure capable of rolling a pre-heating sleeve into place around a drill stem member in such a manner that the sleeve bears against the entire surface of the periphery of the member with substantially equal pressure.

Yet another object of the invention is the provision, in such a machine, of structure capable of holding a pre-heated sleeve around a drill stem member with sufficient expansion when cooled to draw it into intimate and contiguous contact with the member.

Other objects are to provide a device of this class which is simple to operate and which permits rapid reception and removal of the work.

An additional object is to so design a machine for the purposes set forth that the weight of the work itself acts as a medium for aligning the machine therewith, so that the stem member, the sleeve and the machine are all automatically aligned by the weight of the work.

A still further object is the provision of apparatus capable of utilizing either flat plate stock or longitudinally split tubular stock in forming sleeves for re-surfacing drill stem members.

Other objects of the invention will be apparent

from the following description when taken in connection with the accompanying six-sheet drawings, wherein:

Figure 1 is an end elevational view of a preferred embodiment of the device showing its jaws open and depicting a drill stem member in position to be re-sleeved, and the sleeve in a position to be forced into intimate contact with the member;

Figure 2 is a fragmentary end elevation, partially in section, detailing the lower portion of the device;

Figure 3 is a fragmentary end elevation of the upper portion of the device with the jaws closed and clamping a sleeve about a drill stem member in position to be welded, the plumbing arrangement for the power operation being shown in detail;

Figure 4 is a view similar to Fig. 1 showing the jaws closed about the work;

Figure 5 is an elevational side view looking from the right hand side of Fig. 4.

Figure 6 is a fragmentary plan view detailing the cams upon which the work rests when the machine is in operation;

Figure 7 is a fragmentary end elevational view detailing the cams and mounting;

Figure 8 is a top view detailing one of the two sets of rollers used to roll the sleeve into place about a stem member;

Figure 9 is a fragmentary end view of the upper end of one of the jaws showing the rollers of Fig. 8 in place;

Figure 10 is a perspective view of the base frame or cradle support;

Figure 11 is a perspective view of the cradle;

Figure 12 is a perspective view detailing a block used in connection with the cradle of Fig. 11;

Figure 13 is a fragmentary side elevational view, showing apparatus in addition to that disclosed in Figs. 1 to 12, the additional apparatus rendering the device capable of utilizing flat plates in lieu of the split sleeves of the first shown device;

Figure 14 is a similar view showing one step in the operation of the device; and,

Figure 15 is a similar view of another step in the operation of the device.

Like characters of reference designate like parts in all of the figures.

In the drawings:

The reference numeral 20 indicates as a whole a rigid supporting frame, preferably of tubular welded construction, and preferably consisting substantially of two parallel end members 21 and 22 rigidly connected adjacent their opposite ends by parallel side members 23 and 24. The member 21 supports two upwardly extending and converging legs 25 and 26 which are capped by a suitable bearing block 27. The base member 22 has upwardly extending and converging legs 28 and 29 capped by a similar bearing block 30. Bearing caps 31 and 32 are provided for a purpose more fully described hereinbelow. The upstanding legs 25 and 28 are rigidly connected by a horizontal brace member 33 and the legs 26 and 29 are similarly connected by a horizontal brace member 34.

Referring now more particularly to Figure 11, the reference numeral 35 indicates as a whole a cradle consisting of a substantially square metal base or bottom 36 having adjacent each corner upwardly and outwardly extending standards 37, 38, 39 and 40. The standards 37 and 40 are connected rigidly at their upper ends by a horizontal

strap or plate 41, and the standards 38 and 39 are similarly connected at their upper ends by a similar plate 42. The plates 41 and 42 lie parallel with each other and normally reside in a similar horizontal plane. The bottom plate 36 also supports a pair of parallel upstanding standards 43 and 44 which are welded at their upper ends to the bottom surfaces, respectively, of the strap members 42 and 41. A threaded take-up rod 45 has its lower end extending through a raised portion 46 of the bottom plate 36 and is adjustably held in connection therewith by a pair of spaced nuts 47 and 48. The take-up rod 45 is provided for a purpose which will be more fully described hereinbelow.

Across the upper surfaces of the strap members 41 and 42, there is rigidly welded a cam supporting plate 50 (Figs. 6, 7 and 11). The plate 50 has two aligned series of upstanding ears 51, and each series of ears are alignedly perforated to receive pivot pins 52. Pivotaly mounted between the adjacent ears 51 of each series upon the pivot pins 52 are a plurality of cams or rockers 53. The outer free ends of each of the cams 53 are each provided with a roller 54 and the two sets of rollers are mounted in series upon two pivot pins 55

Welded rigidly to the standards 37 and 38 and located between the two is a heavy metal frame consisting of side plates 56 and a connecting end plate or brace 57 extending between the side plates. An outstanding horizontal trunnion 58 is rigidly mounted upon the brace plate 57. A similar frame is rigidly connected between the standards 39 and 40 and consists of side plates 59 and 60 connected thereto. The trunnions 58 and 62 are in axial alignment with each other and are adapted to be journaled in the bearing blocks 27 and 30 of the cradle supporting structure 20. The bearing caps 31 and 32 act in a usual manner to hold the trunnions in place upon the bearing blocks 27 and 30, and usual stud bolts 63 act to hold the caps in place.

From the foregoing description, it will be seen that when the cradle 35 is mounted in the cradle supporting structure 20, it may rock on the trunnions 58 and 62 within the space lying between the horizontal braces 33 and 34. This rocking movement of the cradle 35 is for a purpose more fully described hereinbelow.

Slidably mounted upon the take-up rod 45 is a heavy metal block 64, and a compression spring 65 is provided around the take-up rod 45 and is normally held under compression by a nut 66 threaded upon the upper end of the take-up rod 45. The block 64 has two spaced parallel pivot pins 67 upon which are pivotally mounted the lower ends of two heavy metal jaws 68 and 69. The jaws 68 and 69 extend upwardly within the space lying between the standards 37 and 38, and the standards 39 and 40, respectively, and the upper ends are curved toward each other at a point above the cams 53. Each of the jaw members 68 and 69 are composed of heavy metal plate construction and each has parallel side members 70 and 71. The upper end of the jaws 68 and 69 are each provided with a pair of metal rollers 72, (best seen in Fig. 8) which are mounted for rotation upon the jaws by the provision of a suitable support 73 having parallel arms 74 welded rigidly to the upper end of each of the jaw members. The jaw members are so mounted on their pivot pins 67 that their upper ends may swing toward and away from each other, and when the jaws are swung together, the rollers 72

of each jaw member will meet or contact the rollers 72 of the other jaw member.

As a means for power actuating the upper ends of the jaws 68 and 69 to move from open to closed position, the following structure is provided:

Firmly bolted to the nether surface of the cam supporting plate 50 (Fig. 11) is a block 80 (Fig. 12) which lies between the horizontal strap members 41 and 42 of the cradle 35. The block 80 at each end is provided with alignedly perforated ears adapted to receive pivot pins 81. A rocker arm 82 is pivotally mounted upon each of the pivot pins 81 and extends outwardly beyond the outer edges of the respective jaws 68 and 69 between the side members 70 and 71 forming the same. Each rocker arm 82 has a laterally extending rigid pin 83 which extends horizontally past the two side members 70 and 71 of the respective jaws and the ends of each pin 83 fit into a notch 84 in side members 70 or 71. The rocker arms 82 are each provided on their outer ends with a suitable piston 84 working in a usual manner within a piston housing 85. The piston housing is provided with a suitable stuffing box 86 to surround the rod of the rocker arm and the stuffing box, for each rocker arm is located just beyond the outwardly extending lateral pins 83 which are adapted to fit within the notches 84 in the outer surfaces of the jaw members 68 and 69. The arrangement is such that when a motive fluid is introduced into the housing 85 to force the piston 84 toward the outer end of the housing, the jaws 68 or 69 are forced toward each other through action of the horizontal pins 83. A suitable valve-controlled plumbing connection is provided for controlling the ingress and outlet of motive fluid to the piston chambers 85. This plumbing arrangement is best seen in Fig. 3 and consists of a motive fluid supply-line 96, a hand-operated, two-way control valve 81 and two supply lines 92 and 93 leading to the opposite piston housings or chambers 85.

In utilizing the above-described machine, an arcuate sleeve 100 is placed around a drill stem section 101, or any member which it is desired to re-sleeve, and the two are then placed upon the cams 53. This is done when the jaws are in the open position as shown in Fig. 1. Since in most instances the drill stem section 101 is of considerable length, it is customary to support the other end of the same by a chain hoist or the like; and since it is sometimes difficult to exactly align the other end of the drill stem section 101 with the cams 53, the cradle 35 will automatically swing upon the trunnions 58 and 62, and the cams and jaws will thus consequently automatically align themselves with the drill stem member as soon as one end of the same is placed in the machine. This eliminates the necessity of exactly adjusting the position of the free or outer supported end of the drill stem member to align it with the cams which are supporting the end in the machine. Before being placed in the machine, the sleeve 100 is heated to render it easily bendable, usually to a cherry red, and after the two members of the work have been placed in the position illustrated in Fig. 1, motive power is applied to the piston chambers 85 through operation of the valve 81. This motive fluid forces the upper ends of the jaws to swing toward each other, and acts to roll the sleeve 100 tightly about the drill stem member 101. When this has been done, the work assumes the position substantially shown in Figs. 3 and 4, and

the motive power is held in the piston chambers until a weld can be accomplished along the adjacent edges 105 of the sleeve 100. With the work still held in place as shown in Figs. 3 and 4, a weld may also be accomplished around each end of the sleeve 100. This is possible because of the fact that the sleeve 100 is longer than the width of the jaws 68 and 69. In order for the jaws to reach the position as shown in Figs. 3 and 4, the block 64 must move upwardly along the take-up rod 45 against the action of the compression spring 65. This compression spring acts against the upward movement of the jaws and consequently, exerts a pressure downwardly on the rollers 72. This downward pressure obtains an intimate rolling of the sleeve 100 about the stem member 101 along the entire 360 degrees of the periphery thereof.

It is pointed out that when the work is in the position shown in Fig. 1, the rollers 72 move toward each other in a horizontal plane, substantially even with the axis of the stem member 101, and then, as the power is increased, the rollers roll upwardly and inwardly over the sleeve 100 to roll the sleeve in place about the stem member 101. Since the cam members 53 are pivotally mounted, they rock slightly upon their pivot pins and maintain an equalization of pressure on the lower portion of the sleeve member 100. The coaction of the inner, adjacent edges of the cam members, the rollers 53 of the cam members, and of the rollers 72 of the jaws, is such that a substantially equal pressure is maintained entirely around the sleeve member 100 as it is rolled into place about the stem member 101. The arrangement of the cam members 53 and rollers 54 also make it possible for the machine to operate upon drill stem members 101 and sleeve members 100 having larger or smaller diameters.

Extending horizontally between the two jaw members 68 and 69, is a rod 110 which carries two compression springs 111, adapted to exert a force outwardly against the jaws 68 and 69 so that the jaws may be urged into an open position when the motivating fluid is released from the piston chambers 85. Horizontal pins 112 act as the means for connecting the rod 110 to the jaws 68 and 69 in an obvious manner.

A foot-operated lever 115 is pivotally mounted to the cradle 35 by a pivot pin 116 and its inner end engages beneath the block 64 so that, if desired, the operator may boost the jaw members upwardly against the action of the spring 65. A retrieving spring 117 acts to draw the outer end of the foot lever 115 upwardly.

It has been stated hereinabove that the present method and apparatus is capable of utilizing either flat plate stock or longitudinally split tubular stock for re-surfacing drill stem members. The apparatus and method for utilizing only the longitudinally split tubular stock has thus far been described hereinabove, and the apparatus for applying the method to the use of flat plate stock will next be described. This apparatus is illustrated in Figs. 13, 14 and 15 of the drawings, and consists of mechanical structure which may be added to the apparatus of Figs. 1 to 12 inclusive when it is desired to use flat plate stock.

The horizontal brace 33 of the cradle supporting structure 20 is provided on its lower surface with a bearing or journal 120, (shown in dotted lines in Fig. 13) which rockably supports a horizontally disposed trunnion 121 (also shown in

dotted lines in Fig. 13). The outer end of the trunnion 121 is rigidly connected, by welding or the like to a cylindrical piston housing or chamber 122 within which is operatively installed a piston head 123 and piston rod 124.

A fluid supply line 125 is connected through a suitable two-way valve 126 to two conduits 127 and 128. The conduit 127 leads to the upper end of the piston chamber 122 while the conduit 128 leads to the lower end thereof. By manipulation of a valve handle 129, power fluid may be selectively introduced into the piston chamber either above or below the piston head 123.

The piston rod 124 passes upwardly from the piston chamber through a suitable stuffing box 130, and its upper end is pivotally connected by a pivot pin 131 to the shank end 132 of a heavy metal hook 133. When the piston 123 is at the upper end of the chamber 122, the jaw portion of the hook 133 extends upwardly well past the upper ends of the jaws 68 and 69 if the jaws are in their lowered positions. The relative vertical positions of the hooks 133 and the jaws 68 and 69 are shown in Fig. 13 with the jaws at their lowered positions.

In utilizing this portion of the apparatus, a pre-heated piece (100-a) of flat metal stock is first laid upon the upper surfaces of the jaws 68 and 69 and rests upon the rollers 72. The end of the drill stem section 101 is next placed upon the piece (100-a) and the hook 133 is swung over the section. The valve handle 129 is manually moved to a horizontal position as shown in Fig. 14 to introduce the actuating fluid into the chamber 122 above the piston head 123. Entry of the fluid into the piston chamber forces the piston-head downwardly to the lower end of its throw, and the hook 133 is also drawn downwardly. The piece (100-a) is thus bent downwardly in the middle to contact the cams 53 and assumes substantially the position shown in Fig. 14. The valve 91 (Fig. 3) is next operated to actuate the jaws 68 and 69 as formerly described hereinabove, and are thus brought into the positions shown in Fig. 15.

In reaching these positions, the jaws roll the piece (100-a) firmly about the stem section 101 in the same manner as hereinabove described with relation to the split sleeve 100.

In cases where re-sleeving is being done upon long sections of drill stem, only one piston actuated hook structure is needed. However, if short drill stem sections are to be re-sleeved, the horizontal brace 34 of the cradle 20 may also be provided with a piston and hook structure. In such a case, the two pistons can be arranged to act simultaneously to pull downwardly upon both ends of the section 101.

It is pointed out that the rocking cams 53 make the device adaptable, without adjustment, to take work of various diameters.

We claim:

1. In apparatus for installing a uni-sectional longitudinally split metal sleeve around a cylindrical object, the combination of: a support having aligned spaced horizontal bearings; a cradle rockably supported in said bearings; a pair of jaws having their lower ends pivotally mounted in the cradle in a manner permitting their upper ends to move toward and away from each other; a table carried by the cradle between the upper ends of the jaws; and power operated means for urging the upper ends of the jaws toward each other.

2. In apparatus for installing a uni-sectional

longitudinally split metal sleeve around a cylindrical object, the combination of: a support having aligned spaced horizontal bearings; a cradle rockably supported in said bearings; a pair of jaws having their lower ends pivotally mounted in the cradle in a manner permitting their upper ends to move toward and away from each other; a roller carried by the upper end of each jaw in common positions; a table carried by the cradle between the upper ends of the jaws; and power operated means for urging the upper ends of the jaws toward each other.

3. In apparatus for installing a uni-sectional longitudinally split metal sleeve around a cylindrical object, the combination of: a support; a cradle pivotally mounted on the support to rock upon a horizontal axis; a pair of jaws; means for pivotally connecting the lower ends of said jaws together in a manner permitting their upper ends to move toward and away from each other; means for mounting the jaws to the cradle in a manner permitting their simultaneous vertical movement with relation thereto; a table carried by the cradle between the upper ends of the jaws; and power-operated means for urging the upper ends of the jaws toward each other.

4. In apparatus for installing a uni-sectional longitudinally split metal sleeve around a cylindrical object, the combination of: a support; a cradle pivotally mounted on the support to rock upon a horizontal axis; a pair of jaws; means for pivotally connecting the lower ends of said jaws together in a manner permitting their upper ends to move toward and away from each other; means for mounting the jaws to the cradle in a manner permitting their simultaneous vertical movement with relation thereto; a roller carried by the upper end of each jaw in corresponding positions; a table carried by the cradle between the upper ends of the jaws; and power-operated means for urging the upper ends of the jaws toward each other.

5. Organization as described in claim 3 and resilient means for normally holding the jaws at the lower end of their throw.

6. Organization as described in claim 3 and manually-operated means for urging the jaws upwardly with relation to the cradle.

7. In apparatus for installing a uni-sectional longitudinally split metal sleeve around a cylindrical object, the combination of: a support; a cradle pivotally mounted on the support to rock upon a horizontal axis; a pair of jaws having their lower ends pivotally mounted in the cradle in a manner permitting their upper ends to move toward and away from each other; a table carried by the cradle between the upper ends of the jaws; a plurality of parallel horizontally disposed elements rockably carried by the upper surface of the table for supporting work; and power-operated means for urging the upper ends of the jaws toward each other to engage the work.

8. In apparatus for installing a uni-sectional longitudinally split metal sleeve around a cylindrical object, the combination of: a support; a cradle pivotally mounted on the support to rock upon a horizontal axis; a pair of jaws having their lower ends pivotally mounted in the cradle in a manner permitting their upper ends to move toward and away from each other; a plurality of parallel horizontally disposed work-supporting elements rockably carried by the cradle between the upper ends of the jaws; and power-operated means for urging the upper ends of the jaws to-

ward each other to engage work while being supported by the elements.

9. Organization as described in claim 7 in which the work-supporting elements comprise: a pair of identical members each being arcuate in cross-section, and each member having a pivotal axis located on its convex surface between its edges whereby the two members may rock simultaneously in order to adapt themselves to equally support cylindrically shaped work of various external diameters.

10. Organization as described in claim 8 in which the work-supporting elements comprise: a pair of identical members each being arcuate in cross-section, and each member having a pivotal axis located on its convex surface between its edges whereby the two members may rock simultaneously in order to adapt themselves to equally support cylindrically shaped work of various external diameters.

11. Organization as described in claim 7 in which the work-supporting elements comprise: a

pair of identical members each being arcuate in cross-section, and each member having a pivotal axis located on its convex surface between its edges whereby the two members may rock simultaneously in order to adapt themselves to equally support cylindrically shaped work of various external diameters; and rollers carried by similar edges of the members to permit rotation of the work thereon.

12. Organization as described in claim 8 in which the work-supporting elements comprise: a pair of identical members each being arcuate in cross-section, and each member having a pivotal axis located on its convex surface between its edges whereby the two members may rock simultaneously in order to adapt themselves to equally support cylindrically shaped work of various external diameters; and rollers carried by similar edges of the members to permit rotation of the work thereon.

JOHN F. CAILLOUX.
